UNITED STATES PATENT OFFICE

112,244

DESIGN FOR A COMBINED SIDE LAMP AND BRACKET FOR TRUCKS

Clark M. Bolser, Cedar Falls, Iowa, assignor to
The Bolser Corporation, Cedar Falls, Iowa, a
corporation of Iowa

Application September 23, 1937, Serial No. 71,761

Term of patent 7 years

To all whom it may concern:

Be it known that I, Clark M. Bolser, a citizen
of the United States and a resident of Cedar
Falls, in the county of Blackhawk and State of
Iowa, have invented a new, original, and ornamental
Design for a Combined Side Lamp and
Bracket for Trucks, of which the following is a
specification, reference being had to the accompanying
drawing, forming part thereof.

Figure 1 is a top plan view of a combined side

lamp and bracket for trucks showing my new
design.

Figure 2 is a perspective view thereof.
Figure 3 is a side elevational view thereof; and
Figure 4 is a front elevational view thereof.

I claim:

The ornamental design for a combined side
lamp and bracket for trucks, substantially as
shown.

CLARK M. BOLSER.
